UNITED STATES PATENT OFFICE.

WILLIAM E. NICKERSON, OF CAMBRIDGE, MASSACHUSETTS.

ELEVATOR ATTACHMENT.

SPECIFICATION forming part of Letters Patent No. 357,938, dated February 15, 1887.

Application filed November 15, 1886. Serial No. 218,893. (No model.)

To all whom it may concern:

Be it known that I, WILLIAM E. NICKERSON, of Cambridge, in the county of Middlesex and State of Massachusetts, have invented certain new and useful Improvements in Elevator Attachments, of which the following, taken in connection with the accompanying drawing, is a specification.

The object of my invention is to add to any elevator a device which shall give additional security and not impair in any way the action of the elevator or of any of the safety devices that may be in use on the elevator to which my device is to be applied. This object I attain by the mechanism shown in the accompanying drawing, which shows two cylinders, one in elevation and one in vertical section, the two cylinders being of the class called "oscillators," and have their piston-rods attached to a single crank-pin on a pulley or drum, about which a rope passes, said rope being attached to the carriage of the elevator as a safety-rope. The two cylinders are filled with some fluid, oil being preferred, and have piston-heads provided with escape-orifices, so that the said piston-heads may traverse from one end of the cylinder to the other, but with a gradual movement, so as to check the free delivery of the safety-rope about the drum, and through it to prevent the elevator-carriage from descending any faster than may be safe, even if all of the other sustaining devices fail.

In the drawing I have shown one method of putting my invention in practice, which I will now describe.

A represents a drum about which my safety-rope passes. This rope may pass directly to the winding-drum of the elevator, or it may be coiled onto the drum A, and the drum A be

operated by the engine. If desirable, the safety-rope may pass one or two turns about the safety-drum and have attached to its end a counterpoise.

B represents the frame to which the other parts are attached.

The drum A has a shaft, A', and crank C, in which a crank-pin, C', is inserted.

E E' are two oscillating cylinders, pivoted, respectively, at H and H'.

The piston-rods D and D' serve to connect the piston-heads (one of which is shown at P) to the crank-pin C', so that the drum A cannot revolve without causing a back-and-forth motion of the piston-heads, and as these piston-heads move in tight cylinders filled with oil or other fluid the rapidity of their motion is limited to the speed desired.

The piston-heads may be constructed to fit loosely, and thus allow the inclosed fluid to pass by between the walls of the cylinders and the edges of the piston-heads, or the piston-heads may have orifices to allow of the passage of oil through them.

To compensate for the loss of fluid in the cylinders I attach immediately above the cylinders oil-reservoirs K K, which have a surplus of oil which will flow back into the cylinders in case it is required.

I claim—

The combination of the drum A, safety-rope, crank-arm C, and crank-pin C' with the oscillating cylinders E E' and pistons D D', all operating together, substantially as described, and for the purpose set forth.

WILLIAM E. NICKERSON.
